Attorneys.

UNITED STATES PATENT OFFICE.

JOHN HERSH, OF FAIRHOPE, PENNSYLVANIA.

RAIL CONNECTION.

Application filed May 31, 1922. Serial No. 564,741.

To all whom it may concern:

Be it known that I, JOHN HERSH, a citizen of the United States, residing at Fairhope, in the county of Somerset and State 5 of Pennsylvania, have invented new and useful Improvements in Rail Connections, of which the following is a specification.

My invention relates to rail connections, and has for its object the provision of a 10 novel and improved rail connection whereby the meeting ends of two rails may be connected without the use of bolts and nuts or similar fasteners as are usually employed.

Another object of the invention is to provide a rail connection which can be quickly 15 applied to the meeting ends of two rails, and which when in position will effectually maintain the rails against lateral or tilting movement.

20 A further object of the invention is to furnish a device of the kind stated which is simple in construction, highly efficient in the use for which it has been designed, and which may be manufactured at a relatively 25 small cost.

With the above and other objects in view, as will become more apparent as the description proceeds, the invention comprises a novel combination and arrangement of 30 parts to be hereinafter described and claimed and in order that the same may be better understood, reference is had to the accompanying drawing, forming a part of this specification.

35 In the drawing:

Figure 1 is a side elevation showing the application of my invention;

Fig. 2 is a top plan view;

Fig. 3 is a section on the line 3-3 of 40 Fig. 2, and

Fig. 4 is a detail showing one of the yoke-spreading rods.

Referring specifically to the drawing, wherein the preferred embodiment of the 45 invention is disclosed and in which like reference characters designate like parts throughout the several views, numeral 5 denotes the meeting ends of two rails of the conventional type. Applied to either side of

50 the rails 5 are opposed longitudinally disposed clamping plates 6 and 6^a respectively, each of which has a longitudinal cut away portion in proximity to the bottom inside edge thereof, as shown at 7, to form a chair 55 for the reception of the base portions 8 of the rail.

One of the longitudinal clamping members 6 carries in its inside face a plurality of transversely projecting pins 9 which are adapted to extend through the usual transverse bolt holes at the ends of the rails 5, and into aligned apertures in the inner longitudinal face of the other clamping member 6^a. Upon the outer face of each of the clamping members 6 and 6^a and preferably 60 at the medial portion thereof, is cut a vertical slot 10 leading into a horizontal slot 11 near the top of said member. The slot 11 of each of the clamping members is in the same horizontal plane and the outer 65 portions of said slots 11 are sloped outwardly and terminate short of the ends of the clamping members 6.

The means for holding the clamping members 6 and 6^a against the rail ends will now 70 be described.

A pair of yokes 12 are provided, the in-turned opposed end portions 13 of each, being insertable into the opposed vertical slots 10. The end portions 13 of one yoke having been inserted in the vertical slots 10 of the clamping members 6 and 6^a respectively, the yoke may be pushed vertically upward in said slots to engage in the horizontal slots 11, whereupon it may be slid outwardly to clamp the members 6 and 6^a 85 against the rails 5. The outward slope of the slots 11 toward their ends serves to clamp the rails tighter as the yoke approaches the ends of said slots. The second 90 yoke is applied in the same manner as previously described but is disposed in the ends of said slots 11 opposite from the first yoke. In this way I provide a clamping action upon either side of the rail joint. As a 95 means for maintaining the yokes 12 at points remote from the vertical slots 10, I provide the yokes with sockets in the inner faces of their arms for the reception of rods 14 which are bent as shown in Fig. 4, 100 when inserted into said sockets, and which may be straightened to a more or less degree after their insertion into the sockets to clamp the rails as the occasion may require.

The side members 6 and 6^a have central steps 15 intermediate their ends resting upon the ties, and the vertical edges of said steps 15 act upon the edges of the ties to prevent any longitudinal movement of 110 the clamping assembly. Spike holes or notches may be provided in the longitudi-

nal edges of the clamping members 6 and 6^a adjacent the ends thereof for the reception of spikes 16 for locating the assembly in position. From an inspection of Figs. 2 and 3 it will be noted that the inturned ends 13 of the yokes are beveled to conform to the slope of the respective ends of the slots 11 in which they are placed. In this way a wedging action is had between the yoke ends 13 and the outwardly directed slope of the slots 11 as the yokes are urged toward the ends thereof.

From the foregoing description, read in connection with the accompanying drawing, the application of my invention will be readily understood by those skilled in the art to which it appertains, and while I have described the preferred embodiment of my invention, it will be expressly understood, that I do not propose to limit myself thereto, since various modifications thereof will suggest themselves to those skilled in the art, within the spirit of my invention, the scope of which is set forth in the following claims.

Having thus described my invention, what I claim as new and desire to secure by Letters Patent is:—

1. In a rail connection, the combination with the meeting ends of two rails; of a pair of opposed clamping members having opposed longitudinal recesses near their bottom edges extending throughout their length and forming a chair for the base portions of the rails, each of said clamping members having a vertical slot in its medial portion and a horizontal slot into which each of said vertical slots opens, said horizontal slots decreasing in depth in the direction of their ends, and clamping elements insertable into said vertical slots and slideable laterally in said horizontal slots for holding said rails in position.

2. In a rail connection, the combination with the meeting ends of two rails; of a pair of opposed clamping members having opposed longitudinal recesses near their bottom edges extending throughout their length and forming a chair for the base portions of the rails, each of said clamping members having a vertical slot in its medial portion and a horizontal slot into which each of said vertical slots opens, said horizontal slots decreasing in depth in the direction of their ends, laterally disposed pins rigidly carried in the inner face of one of said clamping members, the meeting ends of said rails having apertures therein through which said pins extend, the other clamping member having sockets into which the ends of said pins extend, and clamping elements insertable into said vertical slots and slideable laterally in said horizontal slots for holding said rails in position.

3. In a rail connection, the combination

with the meeting ends of two rails; of a pair of opposed clamping members having opposed longitudinal recesses near their bottom edges extending throughout their length and forming a chair for the base portions of the rails, each of said clamping members having a vertical slot in its medial portion and a horizontal slot into which each of said vertical slots opens, said horizontal slots decreasing in depth in the direction of their ends, and clamping elements insertable into said vertical slots and slideable laterally in said horizontal slots for holding said rails in position, and means for maintaining said clamping elements in the remote ends of said slots.

4. In a rail connection, the combination with the meeting ends of two rails; of a pair of opposed clamping members having opposed longitudinal recesses near their bottom edges extending throughout their length and forming a chair for the base portions of the rails, each of said clamping members having a vertical slot in its medial portion and a horizontal slot into which each of said vertical slots opens, said horizontal slots decreasing in depth in the direction of their ends, laterally disposed pins rigidly carried in the inner face of one of said clamping members, the meeting ends of said rails having apertures therein through which said pins extend, and the other clamping member having sockets into which the ends extend, clamping elements insertable into said vertical slots and slideable laterally in said horizontal slots for holding said rails in position, and means for maintaining said clamping elements in the remote ends of said slots.

5. In a rail connection, the combination with the meeting ends of two rails; of a pair of opposed clamping members having opposed longitudinal recesses near their bottom edges extending throughout their length and forming a chair for the base portions of the rails, each of said clamping members having a vertical slot in its medial portion and a horizontal slot into which each of said vertical slots opens, said horizontal slots decreasing in depth in the direction of their ends, clamping yokes having opposed inturned ends insertable in said vertical slots and slideable laterally in the horizontal slots toward the shallow ends thereof, the opposed inturned ends of each of said yokes being beveled to conform to the angle of the outward incline of said slots.

6. In a rail connection, the combination with the meeting ends of two rails; of a pair of opposed clamping members having opposed longitudinal recesses near their bottom edges extending throughout their length and forming a chair for the base portions of the rails, each of said clamping members having a vertical slot in its medial portion

- and a horizontal slot into which each of said vertical slots opens, said horizontal slots decreasing in depth in the direction of their ends, laterally disposed pins rigidly carried in the inner face of one of said clamping members, the meeting ends of said rails having apertures therein through which said pins extend, and the other clamping member having sockets into which the ends of 5 said pins extend, clamping yokes having opposed inturned ends insertable in said vertical slots and slideable laterally in the horizontal slots toward the shallow ends thereof, the opposite inturned ends of each of 10 said yokes being beveled to conform to the angle of the outward incline of said slots.
7. In a rail connection, the combination with the meeting ends of two rails; of a pair of opposed clamping members having opposed longitudinal recesses near their bottom edges extending throughout their length and forming a chair for the base portions of the rails, each of said clamping members having a vertical slot in its medial portion and a horizontal slot into which each of said vertical slots opens, said horizontal slots decreasing in depth in the direction of their ends, clamping yokes having 20 opposed inturned ends insertable in said vertical slots and slideable laterally in the horizontal slots toward the shallow ends thereof, the opposite inturned ends of each of 25 said yokes being beveled to conform to the angle of the outward incline of said slots, and said yokes having opposed sockets in the arms thereof and means insertable therein for urging the yokes toward the ends of said horizontal slots and remote from said vertical slots.
- 30 8. In a rail connection, the combination with the meeting ends of two rails; of a pair of opposed clamping members having opposed longitudinal recesses near their bottom edges extending throughout their length and forming a chair for the base portions of the rails, each of said clamping members having a vertical slot in its medial portion and a horizontal slot into which each of said vertical slots opens, said horizontal slots decreasing in depth in the direction of their ends, laterally disposed pins rigidly carried in the inner face of one of 35 said clamping members, the meeting ends of said rails having apertures therein through which said pins extend, the other clamping member having sockets into which the ends of 40 said pins extend, clamping yokes having opposed inturned ends insertable in said vertical slots and slideable laterally in the horizontal slots toward the shallow ends thereof, the opposite inturned ends of each of 45 said yokes being beveled to conform to the angle of the outward incline of said slots, and said yokes having opposed sockets in the arms thereof and means insertable therein for urging the yokes toward the ends of said horizontal slots and remote from said vertical slots.
- 50 9. In a rail connection, the combination with the meeting ends of two rails; of a pair of opposed clamping members, each of said clamping members having a vertical slot in its medial portion and a horizontal slot into which each of said vertical slots opens, said horizontal slots decreasing in depth in the direction of their ends, laterally disposed pins received in the inner faces of said clamping members, the meeting ends of said rails having apertures therein through which said pins extend, and clamping elements insertable into said vertical slots and slideable laterally in the horizontal slots for holding said rails in position.
- 55 10. In a rail connection, the combination with the meeting ends of two rails; of a pair of opposed clamping members, each of said clamping members having a vertical slot in its medial portion and a horizontal slot into which each of said vertical slots opens, said horizontal slots decreasing in depth in the direction of their ends, laterally disposed pins received in the inner faces of said clamping members, the meeting ends of said rails having apertures therein through which said pins extend, and clamping elements insertable into said vertical slots and slideable laterally in the horizontal slots for holding said rails in position.
- 60 11. In a rail connection, the combination with the meeting ends of two rails; of a pair of opposed clamping members, each of said clamping members having a vertical slot in its medial portion and a horizontal slot into which each of said vertical slots opens, said horizontal slots decreasing in depth in the direction of their ends, laterally disposed pins received in the inner faces of said clamping members, the meeting ends of said rails having apertures therein through which said pins extend, clamping elements insertable into said vertical slots and slideable laterally in the horizontal slots, and means for maintaining said clamping elements in the remote ends of said slots.

In testimony whereof I affix my signature.

JOHN HERSH.
